J. M. TWEIT

WRENCH

Filed May 27, 1924

Inventor
J. M. Tweit.

By Attorney

UNITED STATES PATENT OFFICE.

JACOB M. TWEIT, OF HOLCOMBE, WISCONSIN.

WRENCH.

Application filed May 27, 1924. Serial No. 716,232.

To all whom it may concern:

Be it known that I, JACOB M. TWEIT, a citizen of the United States, residing at Holcombe, in the county of Chippewa and State of Wisconsin, have invented certain new and useful Improvements in Wrenches; and I do hereby declare the following to be a full, clear, and exact description of the invention, such as will enable others skilled in the art to which it appertains to make and use the same.

This invention relates to wrenches, and has for one of its objects the provision of a device of this character which shall include a handle through the medium of which the jaws may be easily and quickly adjusted to fit bolt heads and nuts of different sizes, and through the medium of which the jaws may be constantly urged in the direction of each other during the turning of a bolt or nut so as to prevent any casual movement between the wrench and the part being turned.

A further object of the invention is the provision of a wrench wherein the jaws will be positively held against any relative axial or turning movements.

A still further object of the invention is the provision of a wrench which may be used to hold a bolt against movement during the application of a nut thereto or the removal of the nut therefrom.

With the above and other objects in view, the invention consists in the construction, combination, and arrangement of parts hereinafter fully described and claimed, and illustrated in the accompanying drawing, wherein:

Figure 1 is a view in side elevation of a wrench constructed in accordance with my invention,

Fig. 2 is a sectional view taken on a plane extending centrally and longitudinally through the wrench,

Fig. 3 is a detail sectional view taken on the plane indicated by the line 3-3 of Fig. 2,

Fig. 4 is a detail sectional view taken on the plane indicated by the line 4-4 of Fig. 1,

Fig. 5 is a detail sectional view taken on the plane indicated by the line 5-5 of Fig. 2, and

Fig. 6 is a detail view illustrating a

slightly modified construction of the jaws of the wrench.

The wrench comprises a bar 1 which is preferably of elliptical formation in cross-section and which is provided at one end with an inner or relatively stationary jaw 2. The bar 1 is provided with a bore extending throughout the entire length thereof and having a portion 3 of elliptical formation in cross-section and a portion 4 of cylindrical formation. The outer end of the cylindrical portion 4 of the bore of the bar 1 is counterbored to provide a socket 5 in which the inner end of a hollow handle 6 is rotatably mounted. A nut 7 is secured within the inner end of the handle 6 by a screw 8 which due to its location within the socket 5 is held against accidental displacement.

A shank 9 of elliptical formation in cross-section is slidably mounted in the bore of the bar 1, and it is provided at its outer end with an outer or relatively movable jaw 10. The shank 9 has a snug fit in the elliptical portion 3 of the bore of the bar 1 to prevent any relative lateral or rotary movements of the jaws 2 and 10. At its inner end, the shank 9 is provided with a reduced threaded stem 11 which passes freely through a washer or abutment 12 secured by screws 13 within the socket 5 inwardly of the inner end of the handle 6 and which passes through the nut 7 into the handle 6, the stem having screw-threaded engagement with the nut. A spring 14, which surrounds the stem 11, is mounted in the cylindrical portion 4 of the bore of the rod 1 between the washer 12 and a washer 15 positioned upon the stem in contact with the inner end of the shank 9, and serves in conjunction with the handle 6 to prevent the jaws 2 and 10 from having any casual relative axial movements. To prevent the stem 11 from being disconnected from the handle 6 during the outward adjustment of the jaw 10, the stem is provided with a cotter-pin 16, at a point outwardly beyond the nut 7.

Preferably, the jaw 10 is provided with a smooth active face 17 and the jaw 2 with a toothed active face 18, the toothed active face permitting a firm grip to be secured upon a nut or head of a bolt. Both jaws 2 and 10 are provided with flanges 19 which

are adapted to be inserted beneath the head of a round-headed bolt when it is desired to use the wrench for the purpose of holding the bolt against turning movement while applying a nut to or removing it from the bolt. The flanges 19 are located at corresponding sides of the jaws 2 and 10, and they extend beyond the active faces of the jaws, and their inner sides are inclined as shown in Fig. 4. If desired, the wrench may be provided, as shown in Fig. 6, with pipe engaging jaws 2^a and 10^a instead of the bolt and nut engaging jaws 2 and 10. The pipe engaging jaws 2^a and 10^a are provided with toothed arcuate active faces 20 and 21, respectively.

From the foregoing description, taken in connection with the accompanying drawing, it will be seen that the jaws are adapted to be adjusted through a turning movement of the handle 6, and that owing thereto the jaws may be readily adjusted and constantly urged in the direction of each other while the wrench is in use. The spring 14 functions to prevent casual inward movement of the jaw 10 and casual rotation of the handle 6. The flanges 19 on the jaws 2 and 10 adapt the wrench for use as a bolt holder, and when so used the flanges engage the inner side of the bolt head and the jaws engage the lateral sides of the bolt head. If after being applied to the head of a bolt, the wrench is moved into contact with the

part adapted to prevent its rotation, both hands of the operator will be left free to apply a nut to or remove it from the bolt. 35

It should be understood that the drawing is merely illustrative and does not pretend to give exact proportions. Furthermore, the said drawing is illustrative of a preferred 40 construction, it being my expectation that various changes and modifications may be made without departing from the spirit and scope of my invention.

What is claimed is:—

A wrench comprising a bar provided with a bore having circular and non-circular portions, the outer end of the circular portion of the bore being enlarged to provide a socket, a shank of non-circular formation in cross-section slidably mounted in the bore and provided at its outer end with a jaw and at its inner end with a reduced screw-threaded stem, an abutment removably secured within the socket, a spring located within the bore between the shank and abutment, a hollow handle having its inner end removably positioned in the socket in contact with the abutment, a nut threaded on the stem and located within the inner end 50 of the handle, and a nut-receiving element carried by the handle and engaging the nut and located within the socket. 55

In testimony whereof I affix my signature.

JACOB M. TWEIT.
